UNITED STATES PATENT OFFICE.

CHARLES B. HALDEMAN, OF AURORA, KANSAS.

AUTOMATIC PUMP-COUPING.

No. 861,112.

Specification of Letters Patent.

Patented July 23, 1907.

Application filed July 6, 1906. Serial No. 324,871.

To all whom it may concern:

Be it known that I, CHARLES B. HALDEMAN, a citizen of the United States, residing at Aurora, in the county of Cloud and State of Kansas, have made certain new and useful Improvements in Automatic Pump-Couplers, of which the following is a specification.

My invention is an improvement in automatic pump couplers, especially adapted for use with wind mills, and consists in certain novel constructions and combinations of parts as hereinafter described and claimed.

In the drawing Figure 1 is a side elevation of my improvement. Fig. 2 is a top plan view. Fig. 3 is a section on the line 3—3 of Fig. 1. Fig. 4 is a detail perspective view of the lower end of the brace. Fig. 5 is a similar view of the coupler head, and Fig. 6 is a similar view of the sliding frame. Fig. 7 is a section on the line 7—7 of Fig. 3.

In the present embodiment of my invention, a coupler head A comprising a casing a having open ends a', is provided upon its sides with grooves or depressions a² in which is bolted the mill rod B, the said rod being forked at its lower end. The space between the sides of the casing is crossed by a partition a³, dividing the interior of the casing into two longitudinal passages, a relatively wide front passage a¹² and a relatively narrow rear passage a¹³. The forward edge of the casing is provided with a socket a⁴, and below the socket is a plurality of notches a⁵, all for a purpose to be hereinafter described. A brace a⁶ is slidably mounted in the rear passage, and the lower end of the brace is adapted to be coupled to the pump piston a⁸ in any suitable manner. The casing a is of such a length that the brace a⁶ is at no time entirely withdrawn therefrom, the brace thus serving as a guide for the casing whereby to retain the mill rod and the pump piston in substantial alignment with each other.

A coupling lever C is pivoted to lugs a⁷ upon the front face of the brace a⁶ near the lower end thereof, and the said coupling lever is provided with an angular portion c adapted to engage the socket a⁴ when the casing is in proper position. The upper end of this lever is normally maintained in separated relation with respect to the brace a⁶ by means of a spring c³ secured at one end to the brace and resting at its other end against the coupling lever. Plates c' are secured upon each side of the brace a⁶ near its junction with the coupling lever, and the forward ends of the plates project upon each side of the coupling lever whereby to guide the coupling lever and to retain the spring in its proper position.

A pump head comprising a ring c⁴ is adapted to be secured to the top of the pump in any suitable manner, and the said ring is provided with an integral upright arm c⁵ having an angular portion c⁶ extending beneath the coupler head and slotted to permit the passage of the

brace a⁶ and the coupling lever C. A swinging lever c⁷ is pivoted to a lug c⁸ upon the front of the ring, and upon the upper end of the swinging lever is pivotally mounted the pump handle D. The pump handle D is forked as at d', on the outer side of its connection with the swinging lever, and that portion upon the outer side of the fork is grooved upon its under face as at d. A sliding frame d³ is mounted upon the brace a⁶ and the upright arm c⁵, the said frame being provided with longitudinal slots d¹⁰, d¹¹ upon each side between the arm and the brace, and with a friction roller d⁴ upon the outer side of the brace and engaging the same, and the forked arms of the handle are pivotally connected to the frame as at d⁶. It is evident from the description that when the handle is manipulated, the sliding frame will be moved vertically on the brace and upright arm. A second lever E is pivoted between the forks of the pump handle D, and to the inner end thereof is pivoted the end of a link e having journaled thereon in the free end, a friction roller e', moving in the slots d⁵ of the sliding frame d³, and between the coupling lever and the upright arm c⁵. At a point on the coupling lever C adjacent to the plates c', on the brace a⁶, is a notch c⁸, which is adapted to receive the pivot bolt d⁶ connecting the forked arms of the pump handle with the coupling lever C, when the said frame is in contact with the said plates.

In operation, when it is desired to couple the pump handle to the pump, the lever E is moved toward the pump handle D until the said lever rests in the groove on the under face thereof. This movement pushes the friction roller e' toward the brace a⁶, carrying the coupling lever C out of engagement with the socket a⁴, and releasing the piston rod a⁸ of the pump from the coupler head A. Upon elevating the free end of the pump handle, and still retaining the lever E in the before-mentioned position, the sliding frame d³ is moved downward until the pivot bolt d⁶ rests in the notch c⁸ provided therefor in the coupling lever. The pump handle is now connected with the pump piston as long as the lever E is retained in its before-mentioned position. Upon releasing the pump handle, the pressure of the spring c³ tends to move the coupling lever away from the brace, and when the windmill actuates the mill rod B, and the coupler head A, the angular portion of the coupling lever will again engage with the socket a⁴, thus coupling the mill and the pump piston.

It will be evident from the description, that when the lever E is in position against the pump handle, the motion of pumping will automatically couple the piston rod and the pump handle, and that when the pump handle is released, the windmill will be automatically coupled with the piston rod.

It will be noticed from an inspection of Fig. 1, that the angular portion c⁶ of the upright bar c⁵, is provided at the end adjacent to the brace a⁶ with lugs c⁹, against

which the friction roller d^4 of the frame d^3 is adapted to rest when the pump handle is released from the pump.

I claim:

1. An automatic pump coupler for windmills, comprising a casing connected with the mill rod, a brace bar connected with the pump piston and movable through the casing, said casing having ribs on its inner surface for guiding the brace rod, a coupling lever pivoted to the brace bar near the lower end thereof and having an angular portion within the casing, said casing being provided with recesses for receiving the angular portion whereby to lock the pump piston and the mill rod, a spring normally maintaining the coupling lever in engagement with the recesses, a pump head having an arm extending upwardly therefrom, a frame having side members provided with a plurality of longitudinal slots slidably mounted on the brace bar and the arm, a pump handle having a forked end and pivotally connected with the pump head, a bolt traversing the ends of the fork, and the slots in the sliding frame, a lever pivoted on the pivotal connection of the pump handle and the pump head, a friction roller movable in the slots of the sliding frame and engaging the coupling lever, and a link connecting the friction roller and the end of the lever, said coupling lever being provided with a recess adjacent to the lower end thereof for receiving the bolt connecting the pump handle with the sliding frame.
2. An automatic pump coupler for windmills, comprising a casing connected with the mill rod, a brace bar connected with the pump piston and movable through the casing, a coupling lever pivoted to the brace bar near the lower end thereof and having an angular portion within the casing, said casing being provided with recesses for receiving the angular portion whereby to lock the pump piston and the mill rod, a spring normally maintaining the coupling lever in engagement with the recesses, a pump head having an arm extending upwardly therefrom, a frame slidably mounted on the brace bar and the arm, a pump handle having a forked end pivotally mounted on the pump head, a bolt traversing the ends of the fork and the sliding frame, a friction roller mounted in the sliding frame and movable longitudinally thereof, said roller engaging the coupling lever, and means in connection with the handle for moving the roller whereby to force the coupling lever toward the brace rod, said coupling lever being provided with a recess adjacent to the lower end thereof for receiving the bolt connecting the pump handle with the sliding

frame, whereby to connect the pump handle with the pump piston.

3. An automatic pump coupler for windmills, comprising a casing connected with the mill rod, a brace bar connected with the pump piston, and movable through the casing, a coupling lever pivoted to the brace bar near the lower end thereof and having an angular portion within the casing, said casing being provided with recesses for receiving the angular portion whereby to lock the pump piston and the mill rod, a spring normally maintaining the coupling lever in engagement with the recesses, a frame slidably mounted on the brace bar and the coupling lever, a pump head, a pump handle pivotally connected with the pump head and with the sliding frame, means in connection with the handle for forcing the coupling lever toward the brace bar whereby to release the angular portion from the recesses, and means in connection with said handle and coupling lever for coupling them together when the sliding frame is in its lowest position.

4. An automatic pump coupler for windmills, comprising a casing connected with the mill rod and provided with an internal recess, a brace bar connected with the pump piston and movable through the casing, a spring actuated coupling lever pivoted to the brace bar near the lower end thereof and having an angular portion within the casing for engaging the recess whereby to lock the pump piston and the mill rod, a frame slidably mounted on the brace bar and the coupling lever, a pump handle connected with the sliding frame, and means in connection with the handle for forcing the coupling lever toward the brace bar whereby to release it from the casing, and to couple it with the brace bar.

5. An automatic pump coupler for windmills comprising a casing having an internal recess and connected with the mill rod, a brace bar connected with the pump piston and movable through the casing, a spring actuated coupling lever pivoted to the brace bar near the lower end thereof and having an angular portion within the casing for engaging the recess to lock the pump piston and the mill rod, a pump handle, and means in connection with the handle for forcing the coupling lever toward the brace bar whereby to release it from the casing and couple it to the brace bar.

CHARLES B. HALDEMAN.
